Primary Examiner — Jennifer L Watkins(74) Attorney, Agent, or Firm — J. Andrew Reed; Vincent J. Allen; Carstens & Cahoon, LLP(57) CLAIM

The ornamental design for a largemouth tackle backpack, as shown and described herein.

DESCRIPTION

FIG. 1 is a front elevation view of the largemouth tackle backpack;

FIG. 2 is a rear elevation view thereof;

FIG. 3 is a right side elevation view thereof;

FIG. 4 is a left side elevation view thereof;

FIG. 5 is a top view thereof;

FIG. 6 is a bottom view thereof;

FIG. 7 is a left side perspective side view thereof; and,

FIG. 8 is a right side perspective side view thereof.

The broken lines on and adjacent to unshaded surfaces depict portions of the largemouth tackle backpack and form no part of the claim. The broken lines on surfaces with surface shading depict stitching and zipper track and form no part of the claim.
